UNITED STATES PATENT OFFICE

CYRIL FREDERICK JOHNSTON, OF CROYDON, ENGLAND

CARILLON MECHANISM

Application filed November 7, 1927, Serial No. 231,750, and in Great Britain December 23, 1926.

This invention relates to carillon mechanism and has for its object to provide efficient mechanism of this type particularly applicable to apparatus of the kind having 5 pneumatic or fluid operating devices or actions.

The present invention consists broadly of carillon mechanism wherein means are provided whereby the striking blow of a bell or 10 a number of bells whether effected manually or by fluid motor mechanism controlled from a manual can be supplemented by power when required.

In the preferred form of the mechanism 15 the bells are struck by fluid motor mechanism of which the valves are controlled by electric power mechanism of which the circuits are closed by switches operated by the levers or keys of the foot operated notes or the manual, 20 or either when the levers or claviers of the foot key board are coupled with those of the manual.

Each unit of the power mechanism may be 25 provided with two or more motors of the same or different power, and means whereby any of them or any group of them can be brought into operation when desired.

When the bell striking mechanism is operated by, or supplemented by, fluid operated 30 motors, they may be provided with fluid admission controlling valves operated by electric power devices controlled by switches arranged on or near a manual.

Some or all of the bells may be provided 35 with two or more clappers each operated by a separate motor, the motors being adapted to be brought into operation singly, or two or more of them simultaneously, from the manual or key board mechanism.

40 The controlling mechanism for each degree of loudness may be connected to a separate manual so that one manual may be used for normal loudness say *f*, a second for *ff* and a third for *fff*, and when fluid operated 45 mechanism is used for the striking mechanism this may be arranged to control the bells singly or in groups.

Each bell striking motor may be of the same size and connected to a separate supply 50 of motive fluid, each supply of motive fluid

being at a different pressure from the others, or each bell striking motor may have two or more admission valves leading to a common fluid supply under pressure, the controlling mechanism being arranged to bring into operation one of them, or any number of them simultaneously. Also the mechanism transmitting motion from the motors to the clappers may be provided with any suitable kind of relay apparatus. 55

Various manners of carrying out the invention are illustrated diagrammatically by the accompanying drawings wherein Figure 1 is a general view of one form of the apparatus, Figure 1^a a front view of the manual, 60 Figure 2 a modification of the fluid driven element and Figure 3 a modification of the apparatus as applied to a bell having two clappers. 65

In these drawings 2 is one of the bells, and 70 3, 4 and 5 the cylinder of fluid motors say pneumatic motors of which the piston rods 3^a, 4^a and 5^a operate through arms 3^b, 4^b and 5^b fixed on a rocking shaft 6 and operating through the end of the arm 4^b, the rod 7, 75 arms 8 and 9^a fixed on a rocking shaft 9, link 10, the rod 11 of the clapper 12. The rocking shaft 9 of this clapper operating mechanism can also be operated from a clavier 13 of the manual 13^a through a rod 14 and arm 15 fixed 80 on the rocking shaft 9.

The fluid motors in the present example are pneumatic motors having admission valves 3^c, 4^c and 5^c connected by passages 3^d, 4^d and 5^d to a main 16 leading to a source of air under 85 pressure. The valves 3^c, 4^c and 5^c are lifted by electromagnets of which the coils 3^e, 4^e and 5^e are connected to a battery or other source of electricity indicated by 17. The circuits of these coils are closed by switches 13^b on the 90 claviers 13, a similar set of switches 18^b is shown on foot pedals 18.

A controlling switch 19 is provided so that the bells can be rung by the manual claviers 13 or the foot pedals 18. With larger bells 95 such mechanism is insufficient to strike the bells with the desired force hence the manual force may be supplemented by power upon closing the switch 19 thereby enabling the closing of the switch 13^b and 18^b by the 100

manuals and foot pedals which brings into operation the pneumatic power devices for each bell.

In the example illustrated the cylinders 3, 4 and 5 are of different powers so that each will operate the mechanism to strike the bell 2 with the clapper 12 with a blow of different strength from the others and thereby obtain a different degree of loudness from the bell. Switch stops 3^s, 4^s and 5^s are provided for bringing into operation the corresponding cylinders. Thus when the switch stop 3^s is pushed in, circuit from the battery 17 can be closed by the clavier switch 13^b through the lead 3^m contacts 3ⁿ and 3^p lead 3^e, coil 3^c and return lead 20, thereby energizing the electromagnet lifting the valve 3^e and admitting air under pressure to the cylinder 3 so as to impel through the arm rod and link mechanism the clapper 12 against the bell 2. If a heavier stroke is required the switch stop 4^s is pushed in, so that circuit from the battery 17 can be closed by the clavier switch 13^b through the lead 3^m contacts 4ⁿ and 4^p lead 4^e, coil 4^c and return lead 20, thereby energizing the electromagnet lifting the valve 4^e and admitting air under pressure to the larger cylinder 4 so as to impel through the arm, rod and link mechanism the clapper 12 against the bell 2. When a still heavier stroke is required the switch stop 5^s is pushed in, so that circuit from the battery 17 can be closed by the clavier switch 13^b through the lead 3^m, 5^m contacts 5ⁿ and 5^p, lead 5^e, coil 5^c and return lead 20, thereby energizing the electromagnet lifting the valve 5^e and admitting air under pressure to the largest cylinder 5 so as to impel through the arm, rod and link mechanism the clapper 12 with still greater force against the bell 2. The same operations can be effected by each foot pedal 18 by means of the switch 18^b and leads 18^e and 18^p. The pistons of the cylinders 3 are arranged to open an exhaust port when at the lower end of their strokes and suitable springs, weights or other suitable mechanism may be provided for returning the mechanism to its normal position. Also any suitable automatic or non-automatic means may be provided for returning the stop switches 3^s, 4^s and 5^s to their normal positions.

The claviers 13 and foot pedals 18 and rod and arm mechanism 14, 14^a, 14^b, 14^c and 15 may be substituted by a three manual key board, one key board being arranged to control directly a series of switches corresponding to switches 3^s, another a series of switches corresponding to 4^s and a third a series corresponding to 5^s, the pneumatic mechanism being similar to that illustrated by Figure 1.

In a modification of the apparatus illustrated by Figure 1, the three air supply pipes 3^a, 4^a and 5^a instead of being fed by a common supply 16 may each have its own supply of

fluid under a different pressure, and in such a case the cylinders 3, 4 and 5 may be of the same size.

In a modification of the pneumatic motors as illustrated by Figure 2 instead of three cylinder units one large cylinder 30 is used with three valves 3^c, 4^c and 5^c, each operated by mechanism similar to that in Figure 1, the corresponding parts being given the same reference numerals. The object of this modification is to provide a greater volume of air to the cylinder for increasing the velocity of the piston according to which stop switch is pushed in and consequently increase the striking blow on the bell 2.

In the modification illustrated by Figure 3, each bell 2 is provided with two clappers 12 and 40 each being connected respectively by links 12^a, 40^a, arms 12^b, 40^b and 12^c, 40^c fixed on rocking shafts 12^d, 40^d and connected by rods 12^e, 40^e with levers 12^f, 40^f pivoted at 12^g and 40^g and carrying the rods 12^h, 40^h of pistons 12^k, 40^k operating in cylinders 12^m, 40^m, the cylinder 12^m being larger than the cylinder 40^m so as to give a heavier striking blow on the bell 2. The air supply to the cylinders is from a pipe 16 connected by pipes 12ⁿ and 40ⁿ to the respective cylinders and provided with valves 112^c and 140^c, these valves being controlled in a similar manner to those described with reference to Figure 1.

The valves 3^c, 4^c and 5^c of the pneumatic motors instead of admitting fluid directly to the cylinders 3, 4 and 5 may be arranged to operate the pistons of relay mechanism operating the admission valves proper of the cylinders.

The electric lead system shown may be substituted by any other suitable system, also the switch stops may be arranged to close circuit when pulled out instead of when pushed in.

What I claim and desire to secure by Letters Patent is:—

1. Carillon mechanism comprising manually operated means for striking a bell, fluid motor operated means for striking the same bell, and means whereby the fluid motor operated means can be made to supplement the manual means when desired.

2. Carillon mechanism comprising fluid motor operated means for striking a bell, a manual and supplementary fluid motor operated means for striking the same bell, the manual being arranged to bring into operation the first fluid motor and means whereby the two motors can be brought into operation simultaneously when desired.

3. Carillon mechanism comprising manually operated means for operating a bell clapper, fluid operated means for operating the bell clapper, and means whereby when required the fluid operated means can be made to increase the striking force of the bell clapper produced by the manual means.

4. Carillon mechanism comprising fluid

- motor operated means for operating a bell clapper, a manual and supplementary fluid motor operated means for operating the same bell clapper, the manual being arranged to bring into operation the first fluid motor and means whereby the two motors can be brought into operation simultaneously when desired. 5
5. Carillon mechanism comprising manually operated bell striking lever mechanism, fluid motor operated bell striking lever mechanism having electrically controlled valves, a hand operated manual, a foot operated manual, means for coupling both manuals, separate switches for controlling each valve arranged to be closed by operating the corresponding element of the manual, and a main switch, the main switch being arranged to open the circuit of the electrically controlled valves so that the bells can be operated by the manually operated mechanism only when required. 10
6. Carillon mechanism comprising bells having two clappers, fluid motor operating means for operating one of the clappers, fluid motor operated means for operating the second clapper, manually operated means for bringing into operation the first fluid motor, and manually operated means for bringing into operation when desired both motors simultaneously. 15
7. Carillon mechanism comprising bell striking lever mechanism operated by manual force from a manual, bell striking lever mechanism for each bell operated by a multiplicity of pneumatic motors, means whereby any of the motors may be brought into operation simultaneously with the manual means. 20
8. Carillon mechanism comprising lever mechanism for operating the clapper of each bell, a rocking shaft, pneumatic motor mechanism having a multiplicity of motors for operating the clapper of each bell, a manual having elements for imparting a striking force to each bell and provided with a switch closing device, an electrically operated valve for each motor main switch for bringing into a power circuit any of the electrically controlled valves, the rocking shaft being connected to the lever mechanism operating the clapper of each bell and also to the striking elements of the manual of which the switch closing devices bring into operation the power circuit of the valves of the motors. 25
9. Carillon mechanism comprising a bell clapper operating arm, a clapper operating manual of which each element carries a switch, a shaft for rocking the said arm, arms and link mechanism for rocking the said shaft, a series of pneumatic motors, a second rocking shaft having arms operated by each motor and connected to the link and lever mechanism of the first rocking shaft 30
- and also by link and lever mechanism to an element of clapper striking manual, electrically operated valves for each motor having circuits closable by switches arranged near the manual, each switch being arranged to close the circuit for one of the valves and each circuit being closable by the switch on the element of the clapper striking manual. 35
